(57) **CLAIM**

The ornamental design for a hose management system as shown and described.

DESCRIPTION

FIG. 1 is front perspective view of a hose management system;

FIG. 2 is a rear perspective view of the hose management system;

FIG. 3 is a front view of the hose management system;

FIG. 4 is a rear view of the hose management system;

FIG. 5 is a top view of the hose management system;

FIG. 6 is a bottom view of the hose management system;

FIG. 7 is a left side view of the hose management system; and,

FIG. 8 is a right side view of the hose management system. The aspects shown in broken lines show portions of a hose management system, which form no part of the claimed design.
